UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

GAS-PRODUCING APPARATUS.

Application filed September 20, 1921. Serial No. 501,886.

This invention relates to gas generation, and more particularly to the generation of a gas, such as producer gas or the like, from solid carbonaceous fuel.

5 In the generation of gas, such as producer gas, coal gas, and the like, from bituminous coal, lignite, peat, and analogous fuels, considerable quantities of hydrocarbons are evolved. At the high temperatures prevailing 10 within the generating zone, these hydrocarbons exist as gas or vapors. Some of these hydrocarbons are of such character that they are also gases at normal temperatures and pressures, that is they are "fixed gases". 15 Others of the evolved hydrocarbons are of such character that at normal temperatures and pressures they are liquids. Gases thus generated may be utilized without further treatment, as is the case with so called "hot" 20 or "raw" producer gas. Under such circumstances the gas is passed directly from the generating chamber to its place of use and its temperature is maintained sufficiently high to prevent condensation of most of the normally liquid hydrocarbons. However a substantial proportion of these hydrocarbons 25 are condensed and deposited along the walls of the mains through which the gas is conducted. A substantial part of the available 30 heat energy of the fuel is thus lost.

If it is desired to transport the gas to any considerable distance, or to store the gas for future use, it must be treated to remove these condensable hydrocarbons, for otherwise 35 they would condense in the delivery pipes, or storage apparatus, and cause damage and trouble. When the gas is treated to remove these hydrocarbons it is found that the quantity of tar removed from gas, such as producer gas say, made from bituminous coal, will often average in excess of 20 gallons of tar per ton of coal. Many clean producer gas plants gasify several tons of coal per hour, some of them running in excess of ten tons 40 per hour. In such a plant the problem of disposing of the large quantities of tar, which result from its operation, has been, heretofore, a very serious one, and one not satisfactorily solved. And, in addition, the loss 45 in efficiency, in the gas making operation, due to the failure to make these removed hydrocarbons into gas has been quite substantial.

In Patent No. 1,394,043 issued to Harry F. Smith, October 18, 1921, is shown a method 50 of gas generation in which this problem of

gasifying the tar is satisfactorily solved, and in which the problem of handling and disposing of the tar is at the same time solved.

This invention has for its principal object the provision of a method of generating gas, 60 from carbonaceous fuels, of the character referred to above, in which the gasification of such fuel admixed with tar is accomplished, and the disposal of the tar thus effected, at the same time.

Another object of the invention is to provide a fuel for use in this method of gas generation.

Still another object is to provide apparatus for carrying out the invention.

Other objects and advantages will be apparent from the description thereof set out below, when taken in connection with the accompanying drawing.

While this invention is generally applicable to the generation of gas, for purposes of description it is shown and described in connection with the generation of producer gas, and as a preferred form of apparatus for carrying out the invention is shown a gas generating system comprising a suction operated producer.

In the drawing in which like characters of reference designate like parts throughout the several views thereof—

Fig. 1 shows gas generating apparatus embodying this invention, the view being partly in vertical section and partly in elevation;

Fig. 2 is a detail view, in vertical section, of a modified form of fuel preparing and feeding mechanism; and

Fig. 3 is a vertical sectional view of still another modified form of fuel feeding mechanism.

In the gas generating system, shown somewhat diagrammatically, in Fig. 1 the numeral 10 designates the metallic shell of a gas producer, or generator, which is shown somewhat conventionally. The interior of this shell contains the gas generating chamber, within which the fuel bed is contained, a lining 11 of fire brick, or similar material, being provided.

The lower end of the gas generating chamber is closed by means of the grate 12, which supports the fuel bed 13, the upper end being closed by means of the top 14, a fuel preparing and feeding mechanism, designated generally by the numeral 15, being mounted within a suitable opening in the top, to feed

fuel to the interior of the generating chamber. The blast, which preferably consists of moisture laden air is introduced through the opening 16 into the ash pit 17, thence passing upwardly through the fuel bed, where the gas making reactions take place, the generated gas passing out through the off-take 18.

The fuel bed is shown as comprising three zones A, B, and C, these zones being shown, 10 diagrammatically, and no attempt being made to accurately limit each zone. These zones vary in extent, during operation, and the lines of demarcation between them, as shown on the drawing, are entirely diagrammatic in character. For purposes of easier 15 description these zones are designated as the "combustion zone" (A), the "reduction zone" (B) and the "distillation zone" (C). During operation, of the producer, as the air blast 20 passes upward through the fuel bed, the fuel in the zone A is burned to complete combustion the resulting hot products of combustion passing upwardly through the zone B, where the carbon dioxide resulting from the reactions 25 in the zone A is reduced to carbon monoxide, the moisture introduced in the blast being decomposed in the two zones A and B, through reaction with the hot carbon, to form carbon monoxide and hydrogen. The hot 30 gases resulting from the reactions within the zone B pass upwardly through the zone C, which consists largely of fresh or green fuel introduced through the fuel feeding mechanism, raising the temperature of the fuel in 35 this zone sufficiently to cause the driving off or distillation of the hydrocarbons therein. The generated gas passes through the off-take 18 and downcomer 20 into the lower end 40 of the condenser or cooler 21. This condenser has baffle plates 22 arranged therein upon which water is sprayed, which, as it runs downwardly from the baffle plates comes into intimate contact with the upwardly moving gas to cool and wash it. The gas 45 passes out of the condenser through the pipe 23, which is connected to an exhauster or pump 24. The apparatus shown in Fig. 1 comprises a suction operated producer, the exhauster 24 serving to draw the air blast 50 through the fuel bed, and the resulting gases from the generating chamber and to force that gas, under pressure through the remainder of the system. The gas passing from the exhauster is forced through the extractor or separator 25. This extractor may 55 be of any suitable, desired, type; but the type illustrated is that disclosed in the patent to Harry F. Smith No. 1,099,773 issued June 9, 1914, and a detailed showing and description 60 of this extractor is therefore not given. As described in the patent above referred to, the gas as it passes into the extractor contains a tremendously large number of very fine or minute particles of tar, or tar fog, and as this 65 tar fog passes through the extractor it is

agglomerated into larger drops which are of sufficient size to separate out under the action of gravity as the velocity of the gas is slowed down in the separator 26. This separator consists, substantially, of an enlargement in 70 the gas main 27, with the baffle 28 extending transversely thereacross, the enlargement and baffle together serving to slow down the velocity of flow of the gas. As the velocity of the gas is thus slowed down the agglomerated drops of tar carried therein will separate out and collect in the sump or tank 29, the cleaned or purified gas passing on through the main 27, to any desired place of use or storage. 80

The tar heretofore ordinarily present in producer, or other analogous gas, is very heavy and viscous and is extremely difficult of handling. But, as set forth in the above referred to Patent No. 1,394,043, if the tar is 85 removed from the gas and returned to the generating chamber in such wise as to be vaporized along with the volatile matter evolved from the coal in the zone C the character of the tar subsequently removed from 90 the gas will be quite different. As set out in said patent the tar should be so returned to the generating chamber that vaporization thereof is readily accomplished. Where the separated tar is thus returned, at substantially 95 the rate at which it is removed from the gas, the tar subsequently formed is much thinner and more fluent, than is the case when the tar is not so returned. In actual producer practice, when this method of tar return is practiced, the resulting tar has about 100 the consistency of lubricating oil, and its handling is a very simple matter. 100

In the present invention the proper distribution of the tar, as it is returned to the 105 generating chamber, is effected by admixing the tar with the solid fuel, or coal, introduced into the generating chamber.

Connected to the lower end of the sump 29 is a pipe 30, which constitutes the inlet 110 pipe of the pump 31. Connected to the outlet port of the pump, and leading off therefrom, is a pipe 32, to which are connected two branch pipes 33, each of which terminates in a nozzle 34, passing through the wall of 115 the fuel hopper 15. Details of construction of these nozzles are not shown since many of the well known conventional types may be used. In fact it is not necessary that a spray nozzle be used, for the tar may be introduced through the open ends of the pipe 33, or in any other manner which will so distribute it over the fuel in the hopper as to secure substantially uniform distribution throughout such fuel. This hopper is of somewhat conventional construction, being provided with a cover 35, through which fuel is introduced into the hopper, the lower end being closed by the bell closure 36, connected by suitable 120 operating mechanism to the operating lever 125 130

37, which carries thereon a weight 38, to make easier the operation of the device. In feeding fuel into the generating chamber the cover 35 is swung to one side and the hopper 5 filled with fuel, the bell closure 36 being in position to close the lower end of the hopper at this time. The cover 35 having then been closed, suitable manipulation of the lever 37, to cause corresponding movement of the bell 10 closure 36, will cause introduction of the fuel into the gas generating chamber, and proper distribution of that fuel over the fuel bed. The pump 31 functions to pump the tar which collects in the sump 29, through the pipe 32 15 and branch pipes 33 to the nozzles 34 where it is sprayed over the fuel within the hopper 15. The tar is thus uniformly admixed with the fuel within the hopper, being spread over that fuel in the form of a layer or coating. 20 When the admixed tar and coal are introduced into the generating chamber the tar will be uniformly distributed upon the upper level of the fuel bed, so that its vaporization is readily accomplished, the tar being distributed with that uniformity which gives 25 the best results.

As fully set out in the above referred to patent when the tar is thus introduced, so that its vaporization occurs within the zone in 30 which the hydrocarbons are being evolved from the fresh fuel, or within the zone in which the chemical reactions connected with the evolving of those hydrocarbons are still going on, the resulting hydrocarbons which 35 are present in the withdrawn gas are of substantially different character from the hydrocarbons which are formed when the tar is not thus returned. And, since the tar is, in practice, normally returned at substantially the 40 same rate at which it is removed from the gas in the purifying apparatus, the gasifying of this tar adds, materially, to the efficiency of the gas making reactions.

In the apparatus described above the tar is 45 admixed with the fuel within the fuel feeding mechanism itself as the fuel is passing therethrough into the generating chamber. In Fig. 2 is shown a different form of feeding mechanism in which the tar is introduced 50 into the generating chamber along with the fuel, without prior admixture thereof. This apparatus is, in so far as regards the fuel feeding mechanism thereof, similar to the mechanism disclosed in the patent issued to 55 Harry F. Smith, No. 1,425,145, dated August 8, 1922.

This fuel feeding mechanism comprises a hollow cylindrical member 40 extending above the top 14' of the producer and rigidly 60 attached thereto and a cooperating cylindrical member 41, rigidly attached to the top of the producer and extending down into the generating chamber. For purposes of description the members 40 and 41, together, 65 are termed a housing. Rotatably mounted

within the housing is a fuel receiving-distributing member 42, the lower end of which extends a substantial distance beyond the end of the housing and is arranged at substantially a right angle to the longitudinal axis 70 of the housing and of the body of the member 42. This member 42 is rigidly secured to a pipe 43, the upper end of which is fixedly retained within the operating wheel 44. The upper end of the member 42, where it is attached to the pipe 43, constitutes a spider 45, so that fuel may readily pass downwardly through the spider into the member 42. One arm of this spider has a passage 46 therein to which the pipe 43 is connected, the other end being connected to the passage 47 which terminates adjacent the lower end of the member 42, and within the end 48 thereof. And the end 48, of the member 42 is offset a sufficient distance to retain the fuel therein. That is this offset end extends radially such a distance that the fuel therein may come to rest, assuming its normal angle of repose.

The upper end of the member 40 through which the pipe 43 extends is closed, an opening 49 being provided therein, for attachment to a fuel conveyor 50, through which fuel, such as coal, may be fed into the housing, and the receiving-distributing member 42 therein, from any desired place of storage. A gate valve 51 operatively connected by suitable link mechanism 52 to the operating lever 53 being provided for opening or closing the passage. A weight 54, is carried by the handle 53, adapted to normally hold the valve 51 in a closed position.

Connected to the upper end of the hub of the wheel 44 is a pipe 55, which constitutes one element of a swivel joint 56, which may be of any desired conventional description, the joint at its other end being connected to a sleeve 57, within which is threadedly mounted a Venturi tube 58. The other end of the sleeve 57 is connected to the pipe 59, through which steam, or other pressure fluid, may be admitted to force the fuel within the member 42, and offset spout 48 into the producer. A cut-off valve 60 of any desired construction, the specific construction therefore, not being shown, is positioned within the pipe 59. Also located within the pipe 59 is a whistle valve 61, having an operating lever 62 the construction being such that manipulation of the lever 62 will admit blasts of steam, or whatever other pressure fluid may be used, through the pipes 59 and 43 to the fuel distributing member.

Positioned adjacent the venturi 58 is a tank 65, connected to the pump outlet pipe 32, through which tar from the sump 29 is delivered into this tank. Opening into the tank 65 is a pipe 66, the other end of which opens into the pipe 59, the construction being such that pressure within the tank 65, above the tar therein, will be the same as the pressure 130

within the pipe 59. When the whistle valve 61 is opened to introduce a blast of pressure fluid to expel the fuel collected within the device through the spout 48, the pressure within 5 the tank 65 will be built up to correspond with the pressure within the pipe 59. Leading off from the tank adjacent the lower end thereof is a pipe 67 the other end of which terminates within the Venturi tube 58, this 10 end of the pipe constituting in effect a nozzle, the construction being such that, as pressure fluid passes through the pipe 59, tar, from the tank 65, will be drawn through the pipe 67 and mixed, within the Venturi tube, with the 15 pressure fluid passing therethrough, this tar being then introduced into the generating chamber, in the form of a spray, along with the fuel which is blown out of the spout 48. The tar introduced into the generating chamber 20 is thus uniformly distributed over the fuel bed.

The tank 65 is preferably provided with a steam jacket 70, the interior of which is connected to the pipe 59, between the valves 60 25 and 61, by means of the pipe 71. This construction is such that the steam jacket 70 is connected to the source of supply of steam throughout the operation of the device. As 30 stated above, when tar return is practiced in accordance with this invention, the resulting tar is a fluid of substantially the consistency of lubricating oil. No difficulty is normally experienced in aspirating the tar from the tank 65, by means of the Venturi tube construction 35 disclosed. The steam jacket 70 is, therefore, normally not needed. But where the tar is collected within a steam jacketed tank it is rendered more fluent, and it may be desirable, at times, to use such a steam jacketed tank. 40 Also with tar which normally results from the practicing of this method of tar return, the pipe 66 may be dispensed with, the Venturi construction shown being sufficient, of itself, to aspirate the tar. But at times it is 45 desirable to balance the pressures within the tank 65 and the pipe 59 so that the aspirating of the tar will be facilitated. The pipe 66 may, of course, be dispensed with if desired.

Leading off from the pipe 59, between the 50 valves 60 and 61, is a second pipe 75 the other end of which opens into the pipe 59, beyond the whistle valve, a control valve 76, of any desired conventional construction being inserted within this pipe. By means of this 55 pipe 75 a suitable quantity of steam or other pressure fluid is at all times, during operation of the device, introduced into the housing 40-41, to prevent leakage of air or gas therethrough.

60 As described in Patent No. 1,425,145 above referred to, the fuel feeding mechanism of the character shown herein is primarily adapted for accurate control of the distributed fuel, so that it may be "spotted", that is 65 distributed upon any desired part or spot

of the fuel bed. Operation of this fuel feeding mechanism, therefore, causes an admixture of the coal and of the liquid hydrocarbons, or tar, removed from the gas, and a feeding of this admixed fuel to the generating chamber in such manner that it is properly distributed over the fuel bed. Of course, in this form of feeding mechanism, as with the other forms shown herein, the tar admixed with the solid fuel, need not necessarily come from the solid fuel itself but may come from any suitable source. 70

In the forms of apparatus described above the tar is admixed with the fuel as it passes through the fuel feeding mechanism, or is introduced into the generating chamber along with the fuel without prior admixture. If desired the tar and fuel may be admixed with each other and then introduced into the fuel feeding mechanism, through which the 80 admixture is fed into the generating chamber. In Fig. 3 is shown a modified form of apparatus in which the mixing of the tar and coal is entirely independent of the fuel feeding 85 mechanism itself. 90

In the form of apparatus shown in that figure the coal is fed, by gravity or other suitable means, through the pipe 100, from any place of storage or supply, to the mixing chamber 101. Mounted within the mixing chamber upon the shaft 102 is the agitating wheel 103, which has a plurality of agitating arms or fingers, the shaft 102 being rotated in any suitable manner, the fingers being correspondingly rotated to stir up and agitate the fuel within the mixing chamber. Opening through the wall of the mixing chamber are a plurality of nozzles 34', to which tar is supplied through the pipes 33', as is the case with the corresponding parts illustrated in 105 Fig. 1. By means of this construction the tar, which is introduced into the mixing chamber 101, and the fuel which is introduced into that chamber, are thoroughly agitated and mixed, as the wheel 103 rotates, to cause a substantially uniform admixture of the tar and fuel. Leading off from the mixing chamber 101 is a delivery pipe 105, which opens into the inlet pipe 106, of the hopper member 107, a valve or gate 108, operated by a suitable lever mechanism 109, being provided for controlling the introduction of fuel 110 into the hopper member. 115

The top of the hopper is closed by means of the member 110, through which the inlet pipe 106 extends, the lower end of the hopper being attached to the top 14 of the producer and surrounding an opening therein. Positioned within the hopper member 107, adjacent its lower end is a partition 111, provided with a plurality of openings 112. Mounted within the lower end of the hopper member, and extending downwardly into the generating chamber of the producer, through the opening in the top thereof, is a delivery 120 115 130

spout 113, the upper end of which is closed, but provided with a plurality of openings or passages 114, which correspond in shape and size with the openings 112 in the plate 111. This spout member has, at its upper end, a flange 115, rotatably seated within a receiving groove 116, in the hopper member, whereby it is supported, with its upper end in sliding contact with the partition 111. A rotatable shaft 117 extends downwardly through the hopper member the lower end of the shaft being received within a suitable opening in the spout 113. As shown the lower end of the shaft is square, and the opening in the member 113 within which this lower end is mounted is of a corresponding shape, so that rotation of the shaft 117 will cause corresponding rotation of the spout 113. Other means of keying the shaft to the spout may be used. The outer end of the shaft is provided with a gear 118, which meshes with a corresponding gear 119, carried by the shaft 120 connected to any suitable power source. During operation the spout 113 is rotated, thus bringing the passages 114, and the openings 112, into register with each other, to permit the passage of fuel from the hopper 107 through the spout into the generating chamber. The rate of feed of the fuel is dependent upon the rate of rotation of the shaft 117, which in turn controls the frequency with which the openings 112 and the passages 114 register with each other, and the length of time during which those passages remain in register. And the spout 113, as it rotates, distributes the fuel uniformly over the fuel bed within the generating chamber.

The fuel introduced into the hopper 107 consists of tar and coal which are admixed within the mixing chamber 101. And the tar introduced into the generating chamber, in this manner, is therefore distributed uniformly over the top of the fuel bed therein. The invention is described above in connection with a producer constructed to operate upon bituminous coal, the tar removed from the generated gas being utilized for return to the generating chamber along with the coal. This not only increases the efficiency of the gas generator, but also readily disposes of the tar which would otherwise be a serious problem. But the invention is by no means limited to that specific application. If desired the invention may be practiced in connection with the generation of gas from fuel which is substantially free from the hydrocarbons which form tar. Where producer gas is made from anthracite coal or coke for example, there is substantially no tar formed. If desired tar from an outside source may be mixed with such a fuel and fed into the producer for the generation of gas.

While the method herein described, and the forms of apparatus for carrying this

method into effect, constitute preferred embodiments of the invention, it is to be understood that the invention is not limited to this precise method and forms of apparatus, and that changes may be made in either without departing from the scope of the invention which is defined in the appended claims.

What is claimed is:

1. In apparatus of the character described, comprising a gas generating chamber adapted to contain a fuel bed; fuel feeding mechanism comprising, in combination, a hopper member, means for introducing solid carbonaceous fuel, such as coal, into said hopper member; means for introducing liquid hydrocarbons, such as tar, into the hopper member; means within said hopper member for distributing the tar uniformly throughout the mass of fuel within the hopper member to provide a coating of liquid tar on said fuel; and means for introducing the admixed fuel and tar into the gas generating chamber.

2. In apparatus of the character described, having a gas generating chamber adapted to contain a fuel bed; a fuel feeding mechanism comprising a fuel receiving member, opening into the generating chamber, having means whereby the fuel may be received and retained within said member; means for introducing a pressure fluid, such as steam, into the fuel receiving member to force fuel therefrom into the generating chamber and means for introducing fluid hydrocarbons, such as tar into the pressure fluid, whereby said tar will be introduced into the generating chamber along with the fuel.

3. In apparatus of the character described, having a gas generating chamber adapted to contain a fuel bed; a fuel feeding mechanism comprising a housing, a fuel receiving spout rotatably mounted within said housing and extending into the generating chamber, means for introducing into the receiving chamber fuel to be distributed within the generating chamber; a supporting pipe connecting the fuel receiving member to a source of supply of pressure fluid, such as steam; a tank for containing tar, or other liquid hydrocarbons, means for connecting the interior of said tank above the level of the liquid therein to the said fluid pressure supply pipe, means for connecting the interior of said tank below the level of the fluid therein to the interior of said supply pipe for supplying liquid hydrocarbon from said tank to the fluid pressure supply pipe.

4. In apparatus of the character described, having a gas generating chamber adapted to contain a fuel bed; a fuel feeding mechanism comprising a housing, a fuel receiving member rotatably mounted within said housing and extending into the generating chamber, a supporting pipe connected to said fuel receiving member and extending upwardly through said housing, a pressure fluid supply

pipe, a swivel coupling connecting the said pressure fluid supply pipe and the supporting pipe, a constricted portion in said supply pipe in the nature of a venturi; a tank for containing a liquid hydrocarbon such as tar, a pipe connecting the said tank above the level of the liquid therein to the fluid pressure supply pipe above the constriction, and a second

pipe connected at one end to the interior of the tank below the level of the liquid therein and at the other end opening into the said venturi-like constriction. ¹⁰

In testimony whereof I hereto affix my signature.

HARRY F. SMITH.
